UNITED STATES PATENT OFFICE

109,202

DESIGN FOR A TOY ANIMAL

Gertrude Dates Beitler, Detroit, Mich.

Application January 3, 1938, Serial No. 74,066

Term of patent 14 years

To all whom it may concern:

Be it known that I, Gertrude Dates Beitler, a citizen of the United States of America, residing at Detroit, in the county of Wayne and State of Michigan, have invented a new, original, and ornamental Design for a Toy Animal, and of which the following is a specification, reference being had therein to the accompanying drawing, forming a part thereof, wherein

I claim:

The ornamental design for a toy animal as shown.

GERTRUDE DATES BEITLER.
